(57) **CLAIM**

The ornamental design for an inverter as shown and described.

DESCRIPTION

FIG. 1 is a front, right, and bottom perspective view of an inverter in accordance with our new design;

FIG. 2 is a front, left, and top perspective view of the inverter in accordance with our new design;

FIG. 3 is a front elevational view of the inverter in accordance with our new design;

FIG. 4 is a rear elevational view of the inverter in accordance with our new design;

FIG. 5 is a top plan view of the inverter in accordance with our new design;

FIG. 6 is a bottom plan view of the inverter in accordance with our new design;

FIG. 7 is a right side elevational view of the inverter in accordance with our new design; and,

FIG. 8 is a left side elevational view of the inverter in accordance with our new design.

The oblique line shading illustrates a translucent or transparent portion of the inverter. The covers covering the AC outputs and the DC outputs are translucent or transparent. The broken lines in the drawings illustrate the portions of the inverter, which form no part of the claimed design.

1 Claim, 8 Drawing Sheets
